UNITED STATES PATENT OFFICE

JESSE E. GRIFFITH, OF ALBION, NEBRASKA

FENCE TOOL

Application filed May 19, 1928. Serial No. 279,142.

My invention relates to wire stretchers and it includes a number of novel features for simplifying the operation of the wire stretcher.

5 One of the objects of my invention is the provision of a curvature in the gripping jaws such that the maximum amount of gripping action is obtained with the least amount of crushing force.

10 Another of my objects is the provision of a curvature especially in the stationary jaw such that it is possible to turn the wire stretcher a considerable distance around the fence post without any interference of the gripping jaws with the wire.

15 Another of my objects is the provision of grooves in the gripping jaws for more firmly engaging the wire, the depth of the grooves increasing from nothing or almost nothing 20 at the nose ends of the jaws to the maximum depth at the heel of the jaws.

25 Another of my objects is the provision of a wire stretcher construction such that the pivotal movement of the jaws may be controlled and held by the use of one hand only and without a post or other object as an abutment.

30 Another of my objects is the provision of secondary holding means additional to the gripping jaws whereby the loose end of the wire may be transported over considerable distances without the danger incidental to the handling of long coils of loose wire.

35 Another object which I have in view is the provision of a structure related to the secondary holding means whereby the wire will be released from the secondary holding means when the gripping jaws engage the wire.

40 An important object of my invention is the provision of fulcrum and handle members which are arranged in alignment, the fulcrum member being narrow and the wire between the jaws being always in the plane of the fulcrum and handle members.

45 Having in view these objects and others which will be pointed out in the following description, I will now refer to the drawings, 50 in which—

Figure 1 is a view in perspective of my wire stretcher.

Figure 2 is an edge view of the wire stretcher showing the fulcrum and handle members lying in the same plane.

Figure 3 is a plan view showing particularly the curvature of the gripping jaws and showing also in dotted lines the bottom portions of the grooves.

Figure 4 is a sectional view through the jaws adjacent the nose end thereof and showing the slight curvature of the grooves at the contact point when wire of small diameter is gripped.

Figure 5 is a view similar to Figure 4, the section being made at a point toward the heel of the jaws and showing the gripping action against two strands of wire.

Figure 6 is a plan view of the jaw portion of the wire stretcher when used with small wire.

Figure 7 is a similar view showing the position of the two jaws in engagement with wire of medium diameter.

Figure 8 is similar to Figures 6 and 7 but it shows the position of the two jaws acting on heavy wire.

Figure 9 is an illustration showing the manner in which the pivotal movements of the jaws may be controlled and held by the use of one hand only and showing also the manner in which the wire stretcher as a whole may be swung around a fence post in order to produce the proper degree of tension in the wire.

Figure 10 is a plan view of the jaw portion of the wire stretcher showing particularly the function and operation of the secondary holding device for engaging the loose end of the wire for transportation.

The wire stretcher includes a handle member 10 and a fulcrum member pivotally secured thereto at 11 and projecting in both directions from the pivot. The fulcrum member has two parts 12 and 13 which are in effect integral. These two parts 12 and 13 may be formed out of a single piece of metal but they are preferably formed independently and then firmly united as by riveting or welding. The parts 10 and 12 lie in the same plane and

the part 13 is offset relative to the plane of the parts 10 and 12. As shown in Figure 2 the parts 10, 12 and 13 have the same thickness, being preferably cut from the same bar of 5 steel.

The jaw in the movable member is curved in the form of the involute of the circle having the axis of the pivot 11 as a center, this being best shown in Figure 3. The curve of 10 the jaw on the fulcrum member is also preferably in the same form. The jaw on the handle member 10 is heavily ribbed at 14 and the jaw on the fulcrum member is likewise ribbed at 15, the ribs having substantially the width 15 of the body portions of these members so that the jaws are in effect doubled in width. Both jaws are grooved from a point adjacent the nose end of the jaws, the grooves increasing in depth toward the heel ends of the jaws. The 20 depth of the grooves is greatest toward the heel ends of the jaws as shown in Figure 5 and it is least adjacent the nose ends of the jaws as shown in Figure 4, but the grooves preferably terminate short of the nose ends of the 25 jaws.

The wire stretcher is designed primarily for use in stretching barb wire fencing both in the erection of new fences and in the repair of old fences. Because of the sharp 30 barbs this fencing is exceedingly difficult to handle and it usually requires the use of both hands for causing the wire stretcher to engage the wire. In the prior constructions so far as I am aware the fulcrum member is 35 caused to rest against the fence post or other abutment so as to make it possible for the user to close the jaws of the wire stretcher after the wire has been positioned between the jaws. Fence posts, however, are not conveniently placed for this purpose and it is necessary for the user to have some control 40 over the pivotal movement of the jaws in order to manipulate the wire. The member 13 overlapping the handle member 10 is so positioned and shaped that the hand may readily grasp both members 10 and 13 in the manner shown in Figure 9, thus leaving the other hand free to guide the wire between the jaws. As will be seen from that figure, 45 it is possible to open and close the jaws by simply decreasing or increasing the grip of the hand on the members 10 and 13 at a point adjacent the pivot 11.

The wire stretcher is applied to the fence 50 post in the manner shown in Figure 9. After the barb wire has been placed in engagement between the jaws of the members 10 and 12 in the manner shown in Figure 9, leverage is applied to the wire stretcher at 55 the end of the handle member 10. In this manner the fulcrum member 12 of the wire stretcher is forced around the post until the proper degree of tension is obtained. The stretching operation is done by using one 60 hand only, leaving the other hand free to

drive the staple when the wire is under tension. It should be noted particularly that the members 10 and 12 are in alignment and that they are relatively narrow. The advantage of this construction in the present 70 wire stretcher is that it constitutes a firmer fulcrum member for use with fence posts which usually have a more or less irregular surface. If the post is gnarled or has protruding knots, the wire stretcher may slip a little during the initial stretching operation but it will quickly find its seat long before the required degree of tension has been obtained. Since the handle and fulcrum members are in the same plane and since the contact point of the gripping jaws lies in the same plane with the handle and fulcrum members, no torsional effects are produced which in so many cases cause the upsetting 80 of the wire stretcher and the releasing of the wire from engagement with the wire stretcher. Such upsetting is practically impossible in the use of the present wire stretcher even if the fulcrum member bears against the most irregular surfaces.

In building fences it is often necessary that the loose end of the wire be dragged over considerable distances between posts. The barb wire is exceedingly difficult to handle because of the barbs which make it difficult to grasp the wire firmly with the hand. The difficulty is greatly aggravated in dragging the loose end from post to post because of the whipping induced by the uncoiling of the wire from the coil. It would be possible to engage the wire between the jaws of the wire stretcher and to thus move it over the required distances but this necessitates holding the jaws in closed position. If the operator releases his grip on the wire stretcher for an instant, the wire is apt to be released and to whip around with possible serious consequences to the user. For this reason I have provided a notch 16 in the nose end of the handle member 10, this notch being so placed that it is possible to position the loose end of the wire between the jaws and to then bend it over in the manner shown in Figure 10. This holding means affords ample security to prevent the release of the end of the wire when dragging it from post to post. The holding means 16, however, is reinforced by the action of the jaws which assist in holding the end of the wire in engagement with the wire stretcher. An inspection of Figure 10 will also reveal that when the wire has been brought to the post and the fulcrum member has been placed in contact with the post, the tight closing of the jaws will force the wire from the notch 16. In order to prevent this release prematurely from the notch 16, I have shaped the edge of the member 13 in the manner shown in dotted lines at 17 in Figure 10 with a slight incurve in the edge. This permits the closing of the jaws and the curve is 130

so formed that it will not release the wire from the notch until the jaws are sufficiently closed to tightly grip the wire when it is under considerable tension.

In Figure 6 is shown the manner in which a very small wire is engaged between the jaws. In this instance only the nose ends of the jaws are in operative position and the wire is gripped between the jaws at a point where the grooves are shallow as shown in Figure 4. In the case of barb wire which is usually formed of two strands of wire, the gripping action takes place at points somewhat more remote from the nose ends as shown in Figure 6 and the two strands are seated in a deeper portion of the grooves as shown in Figure 5. As will be readily apparent from an inspection of these figures, the wire will find its appropriate seat at the proper point in the jaws and the curved surfaces presented by the grooves will provide a much greater gripping surface than would be provided if the grooves were absent.

Having thus described my invention in such full, clear, and exact terms that its construction and operation will be readily understood by others skilled in the art to which it pertains, what I claim as new and desire to secure by Letters Patent of the United States is:

1. A wire stretcher including a handle member and a fulcrum member positioned in end to end relation and having wire gripping jaws on the abutting ends thereof, and means pivotally connecting said two members together for opening and closing said jaws, the abutting end portion of one of said members being provided with a notch for receiving a looped portion of the wire to be stretched, said notch being so positioned with reference to the edge of the other of said members that the loop of wire will be released therefrom during the final gripping movement of said jaws.

2. A wire stretcher including a pair of members positioned in end to end relation and having wire gripping jaws on the abutting ends thereof, a plate rigidly secured to one of said members and overlapping the other of said members, and a pivotal connection between said plate and said overlapping member, the gripping surfaces of said jaws being in the form of converging curves for gripping wires of different diameters and each of said gripping surfaces being provided with a groove positioned lengthwise thereof for seating the wire to be gripped.

3. A wire stretcher including a pair of members positioned in end to end relation and having wire gripping jaws on the abutting ends thereof, and means pivotally connecting said two members together, the gripping surfaces of both said jaws having con-

vex forms in a lengthwise direction and having concave surfaces transversely thereof.

4. A wire stretcher including a pair of members positioned in end to end relation and having wire gripping jaws on the abutting ends thereof, and means pivotally connecting said two members together, the gripping surfaces of both said jaws being provided with grooves increasing in depth from the nose ends of said jaws toward the heel ends thereof.

5. In a fence tool, a member having a spike portion and an anvil portion, and a handle member pivotally connected to said first named member intermediate the spike and anvil portions thereof for supporting said two portions in working position in a plurality of angular positions relative to said handle member.

6. In a fence tool, wire cutting means including a member provided with a wire holding notch, and a shear blade coacting with said member, the shearing edge of said shear blade being incurved for guiding the wire into the holding notch to facilitate the positioning of the wire in the notch.

7. A wire stretcher including a handle member and a fulcrum member positioned in end to end relation and in a common plane, an offset member secured to and projecting from said fulcrum member and overlapping a portion of said handle member, and a pivotal connection between said handle member and said offset member whereby said handle member and said offset member may be grasped by one hand to control the pivotal movements thereof.

8. A wire stretcher including a handle member and a fulcrum member positioned in end to end relation and in a common plane, jaws on the abutting ends of said handle member and said fulcrum member, an offset member integral with and projecting from said fulcrum member and overlapping a portion of said handle member, and a pivotal connection between the overlapping portion of said offset member and said handle member, the overlapping portion of said offset member having a rounded edge substantially tangential to an edge of said handle member whereby said handle member and said offset member may be grasped by one hand to control the pivotal movements thereof.

In testimony whereof I affix my signature.

JESSE E. GRIFFITH.
